UNITED STATES PATENT OFFICE

2,498,258

METHOD OF PRESSING GARMENT SEAMS

Arthur C. Duske, New York, N. Y., and Raymond H. Reiss, Deal, N. J., assignors to Reiss Manufacturing Corporation, Wilmington, Del., a corporation of Delaware

Application November 2, 1945, Serial No. 626,284

2 Claims. (Cl. 38—144)

1

The present invention relates to a method and means for opening, flattening, and pressing the loose or free edges of a garment seam against the adjacent material of the garment and for imparting to the seam and garment portions near the seam the desired shape or contour. It is particularly useful with respect to the shoulder seams of a coat, jacket, or the like.

When two pieces of garment material are stitched together to form a seam, the loose edges thereof project outwardly from the back of the material or from what eventually constitutes the inside of the garment. In order to provide a smooth seam and to avoid unsightly bulges and ridges, the loose edges should be opened, flattened against the material adjacent the seam, and fixed to remain in such positions. Heretofore, and to a substantial extent, these operations have been performed by use of a sadiron, requiring the services and time of skilled labor which involves considerable expense for such operations. Additionally, it may be desirable to properly shape the seam and garment portions near the seam.

One object of the present invention is to provide a method and means of positioning the loose edges of a garment seam which is effective in obtaining an unusually smooth seam with no bulging, wrinkling or ridging, and thus eliminate an unsightly appearance of the garment and discomfort to the wearer.

Another object of the invention is to provide a method and means whereby the seam and garment portions near the seam can be properly shaped and contoured.

Furthermore, the method of the present invention can be adequately performed by unskilled operators and with greater rapidity than was possible by the previous methods practiced by skilled operators. As a result, the time of completing this operation or similar operations is substantially reduced.

Other objects and advantages of the invention will become apparent from the following description in conjunction with the accompanying claims and drawings.

Referring to the drawings—

Figure 1 is a perspective view of a garment press buck on which is positioned a partially completed garment with the loose edges of a seam closed and projecting upwardly.

Figure 2 is similar to Figure 1 and shows the loose edges of the seam being opened by an instrumentality or tool.

Figure 3 is similar to Figures 1 and 2 and shows the loose edges of the seam completely opened

and the tool resting on and holding down the edges of the seam in a flattened position.

Figure 4 is a perspective and fragmentary view of an ordinary garment press and shows the press head being forced downwardly against the tool and garment on the buck.

Figure 5 is similar to Figures 1, 2 and 3, and shows the loose edges of the seam opened, flattened, and permanently pressed against the adjacent material of a garment.

Figure 6 is a plan view of the instrumentality or tool used in opening and flattening the loose edges of the seam, and

Figure 7 is a sectional view of the instrumentality or tool on the line 7—7 of Figure 6.

Referring to the accompanying drawings, in which like numerals indicate like parts in the several views, the seam is shown, merely for the purposes of illustration, in the shoulder of a man's coat. However, it will be understood that the invention is applicable to the seams of other garments and to other portions of the garment.

The method and means of the present invention may be practiced in conjunction with any ordinary type of garment press used in the clothes manufacturing industry and for the purposes of illustration the garment press shown in Figure 4 comprises generally the press head 10 supported by pivotally mounted arms 11 and the buck 12 supported by suitable frame members fragmentarily shown at 13. The handle 14 is used by the operator to raise and lower the press head, and the lever 15 which is connected with a usual valve arrangement can be manipulated to effect the discharge, in this instance of steam, through the padding or wire screen on the press head, or through the press head alone. It will be understood that a garment press having merely a heated press head without a steaming device can be utilized satisfactorily.

The garment is designated as 16, the seam as 17, and the loose or free edges of the seam as 18.

Referring to Figures 6 and 7, the instrumentality or tool 19 used in practicing the method of the present invention comprises a flat elongated member of foraminous material 20. There may be a multiplicity of plies of the foraminous material, such as wire mesh, as shown at 21. The said member is formed into a point 22 and may be provided with a non-foraminous binding strip 23, such as metal in the form of a channel, secured to its edges. The tool should be of such weight as will hold the loose edges of the seam in a flattened position against the adjacent material of the garment after the said edges have

been opened and spread by the pointed end of the tool. The foraminous material of the tool will permit heat, including steam or hot air, to be directed from the press head of the garment press or other source against the flattened edges of the seam, and this, together with pressure such as is provided by the press head or by some other means, will permanently position or press the seam edges flat against the adjacent material of the garment.

Figures 1 to 5 inclusive illustrate the sequence of operations of the method of the invention. As shown in Figure 1, the garment 16 is placed on the buck 12 of the garment press with the loose edges 18 of the seam 17 projecting upwardly. The operator then manipulates the tool 19 so that its pointed end 22 will separate and spread the said loose edges of the seam for its entire or a substantial part of its length, the tool being so held against the spread edges as to maintain them in this position, as shown in Figures 2 and 3. When such operation is completed, the tool is permitted to remain in the position of Figure 3, and its weight assures that the spread edges of the seam will be flattened against the adjacent material of the garment, one edge on each side of the seam stitching.

The operator then lowers the press head of the garment press in the manner shown in Figure 4, whereupon the lever 15 is manipulated to direct heat through the press head, the foraminous material 20 of the tool, and against the flattened seam edges beneath the tool. At the same time, pressure is applied by means of the press head, and as a result, the flattened seam edges are pressed into substantially permanent positions, as shown in Figure 5.

After the operation just described is completed, the press head is raised, the tool removed, and the garment shifted to bring another seam into place or removed from the buck.

As an alternative sequence of operations, it is sometimes desirable to initially position the loose edges of the seam by a relatively short application of heat and pressure, lift the press head, remove the tool, lower the press head a second time into direct contact with the garment, and again apply heat and pressure to permanently press the edges into position against the adjacent material of the garment. During this sequence of operations and after removal of the tool, the garment may be manipulated or worked into a proper shape before heat and pressure are applied the second time, thereby not only pressing the seam edges into their final positions but also permanently imparting to the garment the desired shape, particularly the shape and contour of the seam and of the portions of the garment near or surrounding the same.

Whether one or two applications of heat and pressure is required depends to some extent on the character of the material of which the garment is made and also the shape and contour desired in the seam. It has been found that with certain textiles, a single application of heat and pressure through the tool will be sufficient.

whereas with other textiles a preliminary application of heat and pressure should be followed by a second application thereof with the tool removed.

It will be apparent that the tool may vary in length, according to the length of the various seams of a garment, and an operator may have several tools of different lengths with which to work. The foraminous portions of the tool, that is the thickness and number of plies, may vary, depending on the necessary degree of heat required to penetrate through said portions to effect the pressing of the seam edges in their final positions and the shaping or contouring of the seam and portions of the garment near or surrounding the seam.

We claim:

1. The method of pressing open the loose edges of a garment seam which consists in pressing the garment on the buck of a conventional garment press with the edges facing upwardly, then spreading and flattening the edges against the adjacent material of the garment by introducing the pointed edge of a substantially flat, foraminous, resilient tool at one end of the seam and moving said tool longitudinally of the seam, said tool being independent of and removable from the press, maintaining the edges flattened by having the tool rest loosely upon the seam and flattened edges, and thereafter applying moisture, heat and pressure independent of the tool over the said tool to press the flattened edges while the said tool is over the seam and edges.

2. The method according to claim 1 wherein after said pressing operation the tool is removed and heat and pressure are applied to finally press the flattened edges.

ARTHUR C. DUSKE.
